(57) **CLAIM**

The ornamental design for a dynamic dispenser, as shown and described.

DESCRIPTION

FIG. 1 is a front perspective view of a first embodiment of a dynamic dispenser;

FIG. 2 is an elevation view of the front thereof;

FIG. 3 is an elevation view of the left side thereof;

FIG. 4 is an elevation view of the rear thereof;

FIG. 5 is an elevation view of the right side thereof;

FIG. 6 is a plan view of the top thereof;

FIG. 7 is a plan view of the bottom thereof;

FIG. 8 is a front perspective view of a second embodiment of a dynamic dispenser;

FIG. 9 is an elevation view of the front thereof;

FIG. 10 is an elevation view of the left side thereof;

FIG. 11 is an elevation view of the rear thereof;

FIG. 12 is an elevation view of the right side thereof;

FIG. 13 is a plan view of the top thereof;

FIG. 14 is a plan view of the bottom thereof;

FIG. 15 is a front perspective view of a third embodiment of a dynamic dispenser;

FIG. 16 is an elevation view of the front thereof;

FIG. 17 is an elevation view of the left side thereof;

FIG. 18 is an elevation view of the rear thereof;

FIG. 19 is an elevation view of the right side thereof;

FIG. 20 is a plan view of the top thereof; and,

FIG. 21 is a plan view of the bottom thereof.

The broken lines shown are for illustrative purposes only and form no part of the claimed design.
